FOLDABLE REFLECTOR

Cameron W. Ostrom, Seattle, Wash.

Application November 6, 1948, Serial No. 58,780

4 Claims. (Cl. 88—90)

1

This invention relates to a foldable reflector for use in photographic work as a means of picking up light rays either from the sun or from an artificial source of illumination and directing the same by reflection upon the object which is to be photographed.

The reflector of the present invention is of that nature employing a multiplicity of leaves of little more than threadpaper thickness each formed to the shape of a sector of a circle and with the sectors being superimposed one upon another and pivoted at the apices to admit of the same being fanned out from an inoperative position whereat the leaves overlie one another to an operating position whereat the leaves act in complement to form a disk-like figure.

As one of its objects, the invention aims to devise a foldable reflector of this character embodying stops to limit the degree to which each leaf is able to move in relation to a next adjacent leaf when the instrument is fanned out to produce the reflector disk, and having a clamping instrumentation made functional upon the pivoted apices to frictionally hold the leaves in operating position.

As a still further object, the invention looks to the provision of a device of the described nature embodying a sustaining stand for the leaves, and which said stand is made extensible and is integrated with a pedestal arranged and adapted when the device is not in use to serve as a housing encasing the free ends of the leaves for protecting these fragile sections against liability of becoming bent or otherwise damaged.

With the above objects in mind, and further aiming to provide a device of simple and inexpensive construction which will be unusually efficient in the performance of the work for which it is intended, the invention consists in the novel construction and in the adaptation and combination of parts hereinafter described and claimed:

In the accompanying drawing:

Figure 1 is a front elevational view illustrating a reflector constructed to embody the preferred teachings of the present invention and showing the several associated leaves fanned out into operating position.

Fig. 2 is a rear elevational view of the device showing the parts as they appear when folded into inoperative position and with the free ends encased within the receiving pocket provided by the stand.

Fig. 3 is a transverse vertical sectional view on line 3—3 of Fig. 2; and

Fig. 4 is an enlarged fragmentary perspective view detailing the stop devices which act to limit the opening movements of the leaves.

Referring to said drawing, the numeral 10 denotes a pedestal establishing a stable footing for the device and produced to the approximate shape of an open-top box, and suitably attached to this

2

box body at a point central to the back wall and projecting upwardly therefrom is a two-part stand composed of associated sections 11 and 12 connected for endwise sliding movement and having a wing-nut 13 permitting the movable section 12 to be clamped in longitudinally adjusted positions. A headed pin 14 is passed from the front side of the stand through the upper or head end of the movable section, and sustained on and movable about this pin as a pivot are the multiple congruent leaves 15 which act in complement to produce the reflector disk of the present invention. These leaves, which are each of sectoral shape, have their apices suitably pierced to fit over the pin and at opposite extremities of their arcuate perimeters are each formed with finger-like projections, as 16 and 17. The fingers 17 are each bent rearwardly at right angles to the plane of the leaf into overlying relation to the rim of the proximal leaf which lies to the immediate rear thereof, and in such a manner, more especially, as will cause each said finger 16 to interrupt the travel of the fingers 17 as the leaves are spread. In fanning out the leaves, it thus becomes necessary only that the operator hold the rearmost leaf stationary and swing the foremost leaf through somewhat less than a full circle of travel, this foremost leaf and each following leaf in the series acting successively to pick up and swing the next adjacent leaf as its hooking finger 17 is brought up against the stop finger 16 of the next adjacent leaf. While not illustrated in the drawing the hooking finger of the rearmost leaf, rather than being bent rearwardly, is or may be brought forwardly such as will enable the same to be releasably caught over the rim of the foremost leaf when the multiple leaves have been fanned out into the positions in which they are shown in Fig. 1. The several leaves are caused to be frictionally held in any given position through clamping pressure exerted from a wing nut 20 threaded upon the pivot pin 14.

The leaves which I employ are of threadpaper thickness and are composed of any material suitable for the purpose such, for example, as sheet aluminum, plastic or thin cardboard, and peculiarized in the instance of any such material by the provision upon the leaf's frontal face of a glazed surface capable of efficiently reflecting light rays. The leaves which I prefer to employ are flat but the same can, if desired, be slightly curved in a direction lengthwise of the leaf to produce, when fanned out, a dished reflector.

It is here pointed out that the leaves, while I have indicated the same as being in exact back-to-back registration when folded together, actually occupy an echelon arrangement due to the hooking fingers of the successive leaves contacting one another, the forward edge of one against the back edge of another. These hooking fingers need have little width, however, and the actual

projection of one beyond another of the folded leaves is consequently very slight.

When folded together into a layered mass, the several leaves have a combined width and length at the outer or butt end substantially in mating correspondence with the box cavity of the stand 10, and the extensible nature of the mounting stand permits this stand to be then drawn upwardly toward the pivot and into housing engagement over said butt whereupon the wing nut 13 is tightened to localize the stand.

It is here pointed out that an effective reflection of light from the reflector demands that the glazed reflective faces of the several leaves be of such a nature as to effect a diffusion of the light. From numerous experiments with collapsible reflectors where, as in the present device, the component leaves necessarily lap one another and hence occupy slightly offset planes, it has been my finding that where the leaves are smooth-faced the light rays cast therefrom travel along disorganized paths which are incapable of being effectively controlled and there appears upon the photographic negative numerous light spots which destroy the clarity of the picture. A highly effective means for diffusing the light is to employ leaves having their reflective faces slightly embossed, giving much the impression of a hammered surface. When so treated, the reflector is free of glare and a general diffusing of the light results to give to photographs of the illuminated object a soft tone suggestive of the professional's work.

I am aware that there is shown and described in U. S. Pat. No. 1,813,102, issued July 7, 1931, a foldable reflector bearing some resemblance to the present invention. Such patented reflector, aside from its employment of smooth-faced leaves, is expressly engineered to permit of the reflection of light rays from a lamp carried centrally thereof, and hence has the objection, from a photographic consideration, of placing the source of light to the front of the object being photographed. The present reflector is primarily aimed to provide a means by which an amateur photographer, using only a single source of light, is enabled to obtain results approaching those which a commercial photographer procures from a severality of strategically placed light sources, and this is to say that the operator can have the source of light, which may be the sun, located to the rear or to either side of the object being photographed, and then cast diffused light upon the front of the object by reflection. Unusually effective high-lighting can be obtained.

It is thought that the invention and the manner of its usage will have been clearly understood from the foregoing detailed description. I intend that the hereto annexed claims be given a scope fully commensurate with the broadest interpretation to which the employed language fairly admits.

1. A foldable reflector comprising, in combination: a plurality of thin sectoral-shaped congruent leaves each having a reflective surface upon one face, and arranged, when not in use, to overlie one another in a layered mass, said leaves being pivotally connected at the narrow or apical ends to permit the leaves to be fanned out and produce a disk-like reflector, a stand having said pivotal connection mounted at the head end thereof, and a pedestal for the stand, said stand being adapted to permit said leaves to be moved from a raised position wherein the

leaves are above the pedestal to a lowered position wherein they engage the pedestal, said pedestal being adapted to fit over and protect the wide ends of the leaves when they are brought together in said layered mass into said lowered position.

2. A foldable reflector comprising, in combination: an extensible stand, a plurality of thin sectoral-shaped congruent leaves each having a reflective surface upon one face and arranged, when not in use, to overlie one another in a layered mass, a connection from the head of the stand to the narrow or apical ends of the leaves permitting the leaves to be pivotally spread and fanned out to produce a disk-like reflector, and a pedestal for the stand which, by a shortening of the stand coincident with the act of folding the leaves into said layered mass, is adapted to fit over and protect the wide ends of said leaves.
3. A foldable reflector comprising, in combination: a plurality of sectoral-shaped congruent leaves each having a reflective surface upon one face and produced from thin sheet stock with the apices apertured, said leaves in use being arranged and adapted to be placed one in overlying relation to another with said apertures in registration, an extensible supporting stand apertured at its head end, a headed pin passing through said registering apertures of the leaves and the aperture of the stand to serve as a pivot connecting the leaves and permitting the latter to be fanned out for producing a disk-like reflector, a nut threadedly associated with the pin to act with the head of the latter for exerting clamping pressure upon the pivoted apices of the leaves to frictionally hold the leaves against relative movement and a pedestal for the stand adapted to house the wide ends of the leaves when the leaves are in a layered mass and the stand is shortened to bring the leaves into engagement with the pedestal.

4. A foldable reflector comprising, in combination: a plurality of sectoral-shaped congruent leaves each having a reflective surface upon one face and produced from thin sheet stock, a supporting stand, means pivotally supporting said several leaves from the head end of the stand to permit the same to be fanned out from an inoperative layered mass into an operating disk-like body, said pivotal connection comprising a nutted pin operating by the act of taking up on the nut to subject the leaves to releasable clamping pressure for frictionally holding the leaves against relative movement, and a pedestal for the stand, said stand being adapted to permit said leaves to be moved from a raised position wherein the leaves are above the pedestal to a lowered position wherein they engage the pedestal, said pedestal being adapted to house the wide ends of the leaves when they are brought together in said layered mass into said lowered position.
